US00D797074S

(12) **United States Design Patent** (10) **Patent No.:** **US D797,074 S**
(45) **Date of Patent:** **** Sep. 12, 2017**

(54) **BIOINTERFACE HEADSET**

(71) Applicant: **Halo Neuro, Inc.**, San Francisco, CA (US)

(72) Inventors: **Matty Martin**, San Francisco, CA (US); **Tal Bar-Or**, San Francisco, CA (US); **Colin Davis**, San Francisco, CA (US); **Victoria Hammett**, San Francisco, CA (US); **Daniel Chao**, San Francisco, CA (US); **Brett Wingeier**, San Francisco, CA (US); **David Kaufman**, San Francisco, CA (US)

(73) Assignee: **Halo Neuro, Inc.**, San Francisco, CA (US)

(**) Term: **15 Years**

(21) Appl. No.: **29/553,513**

(22) Filed: **Feb. 2, 2016**

(51) LOC (10) Cl. **14-01**

(52) U.S. Cl.

USPC **D14/205**

(57) **CLAIM**

The ornamental design for biointerface headset, as shown and described.

DESCRIPTION

FIG. 1 is an isometric view, from the front left, of the biointerface headset.

FIG. 2 is an isometric view, from the back right, of the biointerface headset, the opposite central circular member is not part of the claimed design.

FIG. 3 is an elevation view of the front of the biointerface headset.

FIG. 4 is a plan view of the bottom of the biointerface headset.

FIG. 5 is a plan view of the top of the biointerface headset.

FIG. 6 is an elevation view of the back of the biointerface headset.

FIG. 7 is an elevation view of the left of the biointerface headset; and,

FIG. 8 is an elevation view of the right of the biointerface headset.

The broken lines depict environment that forms no part of the claimed design.

1 Claim, 4 Drawing Sheets
